PORTABLE OIL WELL DERRICK

Ridley Woods, Long Beach, Calif.

Application September 10, 1949, Serial No. 114,959

7 Claims. (Cl. 189—11)

1

My invention relates to the field of oil well equipment, and more particularly to a portable derrick that can be used not only for oil well drilling purposes, but due to the mobile nature of the device, can be utilized to advantage wherever a relatively high mast or derrick is required such as for the mooring of a dirigible, as a temporary television or radio tower, and similar uses.

Although a number of portable oil well derricks have been devised and used in the past, the majority of these devices are formed as a single mast which may be erected at the desired location, and when the drilling or oil well maintenance operation is completed can be taken down and moved to the next location. The disadvantage of this type of derrick is that it is in the form of a single mast, and requires the use of guy wires to hold it in an erect and stable position. The use of guy wires on such a device is not only inconvenient, but is time consuming in that means must be provided to anchor the lower ends of the guy wires in order that they will maintain the mast in a stable position.

The major object of my invention is to provide a portable oil well derrick which in the collapsed state is in the form of a compact unit that can be moved from place to place, and upon the desired location being reached the unit by use of hydraulic equipment formed as a part thereof is erected into a tripod type oil well derrick requiring no guy wires to maintain it in a stable position.

Another object of my invention is to furnish a portable oil well derrick that can be moved over the highways in the same manner as any other vehicle, can be erected and collapsed by a member of a drilling crew after the man has received a relatively short course of instruction in the operation of the device, and is economical to operate in that the device requires little or no maintenance attention.

Yet another object of my invention is to supply a portable oil well derrick that can be fabricated from standard commercially available materials, is attractive in appearance, is compact and can be stored in a relatively small area when not in use, can be fabricated without the use of special machinery and plant equipment, and can hence be sold at a price which is competitive with other oil well derricks of a portable nature.

These and other objects and advantages of my invention will become apparent from the following description of a preferred form thereof and the drawings illustrating that form in which:

Figure 1 is a side elevational view of my port-

2

able oil well derrick in the collapsed state, and ready to be moved to a drilling location;

Figure 2 is a plan view of the derrick shown in Figure 1;

Figure 3 is an end elevational view of the device shown in Figure 1 and taken looking from the left in Figure 1;

Figure 4 is a side elevational view of the device with one of the legs extending upwardly in a nearly raised position, and the two other legs, one of which is hidden from view, in the process of being raised to form the derrick tripod;

Figure 5 is a fragmentary horizontal view of my device showing the manner in which the rearward portion of the vehicle is spread prior to the two legs supported therefrom being erected to form a portion of the derrick;

Figure 6 is a perspective view of the derrick in an erected position;

Figure 7 is a horizontal cross sectional view of one of the tripod legs taken on the line 7—7 of Figure 4;

Figure 8 is a fragmentary perspective view of one of the lower portions of a leg being erected to form a portion of the derrick;

Figure 9 is a fragmentary perspective view of a portion of one of the tripod legs, and showing the manner in which the upper portion thereof is supported from the lower portion of the leg;

Figure 10 is a plan view of the working platform; and,

Figure 11 is a schematic layout of the hydraulic system used in actuating the component parts of my portable oil well derrick.

Referring now to Figures 1, 2, and 6 for the general arrangement of my invention, it will be seen that a vehicle V is provided that pivotally supports three tripod legs L-1, L-2, and L-3 therefrom. The vehicle V, as may best be seen in Figure 6, is adapted to have the rearward portion thereof spread to permit the legs L-1, L-2 and L-3 to be erected into a position where they form a derrick D, with the derrick having a working platform P supported at a convenient height thereon. The derrick D after it has been erected by the use of a hydraulic mechanism H best seen in Figure 11, may be collapsed after the drilling operation has been completed into the form shown in Figures 1 and 2 by the use of the hydraulic system H used in placing the derrick in an erected position.

The vehicle V as may best be seen in Figures 1, 4, and 5 is formed from a forward chassis portion 10 having two identical rearwardly ex-

tending chassis portions 11 pivotally affixed thereto. The forward chassis portion 10 is fabricated from two parallel laterally spaced members 12 which are joined at the forward end by a cross piece 13 and on the rearward end by a cross member 14. The cross member 14 has two laterally spaced U-shaped members 15 projecting rearwardly therefrom. Situated in each of the U-shaped members 15 is a sleeve member 16 that is rotatably supported on a shaft 17 that extends between the two spaced legs forming the U-shaped member. A pin 18 is provided for and extends upwardly from each of the sleeve members 16, and pivotally engages a horizontally positioned lug 19 disposed on the forward end of each of the rearward chassis portions 11.

Each of the chassis portions 11 as may best be seen in Figure 5 includes two laterally spaced side members 20 that are joined on their rearward ends by a cross piece 21, and on their forward ends by a cross member 22 to which the lugs 19 are welded or otherwise affixed. In Figure 1 it will be seen that the forward chassis member 10 is movably mounted on pneumatic tired wheels 23, while each of the rearward chassis portions 11 is supported on a set of pneumatic tired wheels 24 that are normally aligned with the wheels 23. Each set of the wheels 24 is mounted on a carriage 25, with each carriage being pivotally supported for horizontal rotation from one of the chassis portions 11.

Each of the carriages 25 has a horizontally disposed gear 26 affixed thereto, with the gear 26 being adapted to engage a worm 27. The worm 27 is mounted on a horizontally disposed shaft 28 which by a conventional bevel gear arrangement 29 provided at the forward portion thereof can be rotated by use of a shaft 30 which extends upwardly a short distance above the chassis 11. The shaft 30 may be manually operated by use of a wheel or crank 31 mounted on the upper end thereof, or it may be power driven should it be so desired. By rotating the shaft 30 the worm 27 is actuated to turn the carriage 25 to a position substantially normal to the longitudinal axis of the chassis 11, and with the wheels 24 so positioned the chassis portions 11 may be swung outwardly from the position shown in phantom line in Figure 5 to that shown in solid line in the same figure for reasons which will hereinafter be explained.

A wheel pin 32 is mounted on each of the inwardly positioned chassis side members 20, with each of the pins pivotally engaging the outer portion of one of two links 33. Each of the links 33 has a hole bored toward the inwardly positioned end thereof that is pivotally engaged by a pin 34. The pin 34 is mounted on the rearward end of a piston rod 35 that extends forwardly into a double acting hydraulic cylinder 36, and by conventional piston means (not shown) provided in the cylinder the rod 35 may be moved forwardly or rearwardly. The motive power to move the rod 35 is provided by the flow of hydraulic fluid to one end or the other of the cylinder 36, and results in the chassis portions 11 being swung outward or inward on the supporting pins 18. Thus, with the wheels 24 properly positioned, the chassis portions 11 may be positioned in alignment with the forward chassis portion 10, or spread to the position shown in full line in Figure 5. The cylinder 36 is preferably supported from the chassis portion 10 on one or more transversely positioned members 37

situated forwardly from the cross member 14 and extending between the side members 12.

Situated on the forward end of the chassis 10 are two upwardly and outwardly extending supporting members 38 that have horizontal bores formed in the upper portion thereof through which a horizontally positioned pin 39 extends. The forward end of each of the chassis side members 12 supports a longitudinally extending beam 40 on the upper surface thereof, with each of the beams having the lower end of one of the members 38 welded or otherwise affixed thereto. An angularly disposed reinforcing bar 41 is provided for and extends between each of the beams 40 and the member 38 supported thereon. The pin 39 as may best be seen in Figure 4 serves to pivotally support the leg L-1 by engaging a bore formed in a lug 42 that extends inwardly from the lower portion of the leg.

20 To pivot the leg L-1 from the horizontal position shown in Figure 1 to the upwardly extending position shown in Figure 4 a hydraulic cylinder 43 is employed. The lower portion of the cylinder 43 is formed with a downwardly extending lug in which a horizontally disposed bore is formed that engages a pin 44 which extends through a similar lug affixed to the forward upper portion of the chassis portion 10. Thus, the hydraulic cylinder 43 may pivot as a piston situated therein (not shown) moves a piston rod 45 upwardly or downwardly due to the introduction into or withdrawal of hydraulic fluid from the cylinder. The rod 45 on its upper end engages a pin 46 mounted in a lug 47 which is secured to the lower inner surface of the leg L-1. The leg L-1, as well as each of the legs L-2 and L-3, are formed with identical lower leg portions 48. The lower leg portions of the legs L-2 and L-3 are designated 48b and 48c respectively.

40 Although the leg portions 48 can be fabricated in a number of different ways, I have found it preferable to use four parallel, laterally spaced members 49 (Figures 7 and 9) which at uniform longitudinal intervals are joined by normally disposed bars 50, with the bars 50 having angularly disposed bracing rods 51 extending therebetween. Each of the leg portions 48 on the lower portion thereof terminates in four inwardly tapering members 52 that on their lower extremity support a plate or member 53 having a jack 54 of conventional design supported therefrom. The jack 54 may be of a simplified structure in which a threaded rod 55 engages a tapped bore provided in the plate 53, with the rod on its lower end rotatably engaging a fixed pressure plate 56 shown only in Figure 6 that is positioned on the surface of the ground.

55 Mounted on the rearward end of each of the chassis portions 11 (Figure 8) are two upwardly and outwardly extending members 57 which on their upper ends support a horizontally positioned pin 58 therebetween. The members 57 preferably extend upwardly from beams 59 that rest on the members 20, and being reinforced by members 60 that extend forwardly from the members 57 to the beams 59. Each of the pins 58 pivotally supports one of the legs L-2 or L-3 by engaging a bore formed in a lug 61 that extends downwardly from the leg. The legs L-2 and L-3 are each pivoted upwardly or downwardly by the use of a hydraulic arrangement as discussed in connection with the leg L-2. The hydraulic cylinders and piston rods used to pivot the legs L-2 and L-3 are hereinafter referred to as 43b, 43c and 45b, 45c respectively.

The leg L-1 as may best be seen in Figures 4 and 7 includes not only the lower leg portion 48, but a leg portion 66 of similar design but of smaller cross section that slides within the confines of the leg portion 48. In legs L-2 and L-3 the same type structure is used with the telescopically movable upper leg portions being referred to as 66b and 66c respectively. Longitudinally positioned within the confines of the leg portions 66 is a hydraulic cylinder 67 that extends substantially the length of the leg portions 48, with the cylinder being supported from the lower part of the leg portion 48 by a transversely positioned pin or member 67' that extends between two oppositely disposed bars 50. The cylinder 67 is provided with a piston rod 68 that is connected to a piston of conventional design (not shown) slidably disposed within the confines of the cylinder, and the upper end of the rod being connected by a pin 69 or other means to the upper portion of the telescopically slidable legs 66. The legs L-2 and L-3 are similarly provided with hydraulic cylinders which are referred to as 67b and 67c respectively.

By use of one of the cylinders 67 the particular leg portion 66 associated therewith can be moved upwardly or downwardly when any one of the legs L-1, L-2, or L-3 is situated in an upwardly and inwardly extending position as occupied by L-1 in Figure 4. The upward and downward movement of each of the leg portions 66 is, of course, controlled by admitting or withdrawing hydraulic fluid from the cylinder 67, 67b, or 67c associated therewith as will hereinafter be explained in detail.

Each of the legs L-1, L-2, and L-3 near the upper portion thereof, as may best be seen in Figure 9, is provided with two oppositely disposed shafts 70 that are rotatably supported by brackets 71. Extending upwardly from each of the shafts 70 are two laterally spaced stops 72 which can be positioned by rotation of the shafts 70 to have the lower end portion of one of the legs 66 rest thereon. The end of each of the shafts 70 is provided with a lever 73 that is pivotally connected to one of two piston rods 74. Each of the rods extends inwardly into a hydraulic cylinder 75 where it is connected to an individual piston (not shown). By use of hydraulic fluid admitted to the cylinder 75 the pistons are either moved away from one another to disengage the stops 72 from their supporting position for the leg 66, or are moved inwardly toward one another to place the stops in a supporting position for the leg. The upward movement of each of the legs 66, 66b, and 66c is controlled by use of the hydraulic cylinder 67, 67b, and 67c associated therewith, or other means that will hereinafter be discussed. The legs 66, 66b, and 66c after they have moved upwardly a predetermined distance, have the lower portion thereof engage stops of a conventional nature (not shown) affixed to the supporting leg portions 48, 48b, and 48c respectively.

Mounted on the upper end of the leg 66 as may best be seen in Figures 1, 2, and 4 is a rectangular framework 76 formed of two laterally spaced parallel side members 77 that are connected by two end pieces 78. Extending upwardly from the framework 76 and supported thereon is a crown block 79 of conventional design that serves when the three legs L-1, L-2, and L-3 are in an erect position to support cables from which a traveling block (not shown) is suspended in accordance with normal oil field practice. Two sheaves 75

80 and 81 are situated on each side of the crown block 79, and can be supported from either the frame 76 or the crown block 79 should this be found to be more convenient.

Two brackets 85 extend outwardly from the upper end portion of the leg 48, and have a shaft 86 extending therebetween that pivotally supports a tubular member 88 to which the working platform frame P is affixed. The platform frame P as may best be seen in Figure 10 includes two angularly disposed arms 89 that on their outer ends are connected by an arm 90. The arms 89, as well as the arm 90, are provided with upwardly extending rails 92, 93, and 94 to safeguard the member of a crew when he is stationed on the platform.

It will be noted that two floored areas 95 and 96 are provided on the platform frame P for use of the crew member stationed on the platform, and that a number of spaced rigid members 97 are positioned within the confines of the platform. The members 97 are used in racking pipe and tubing in accordance with standard oil field practice.

Mounted on each end of the leg 90 is a pin 90a that pivotally supports an engaging member 98, with each of the members being adapted to be removably affixed to one of two hooks 99. Each of the hooks extends inwardly from one of the legs L-2 or L-3. The members 98 are caused to engage the hooks 99 after the legs 48, 48b, and 48c have been erected, but prior to the legs 66, 66b, and 66c having been moved upwardly to form the completed derrick as will hereinafter be explained. The engaging members 98 and hooks 99 cooperate to hold the platform frame P in a substantially horizontal position as may best be seen in Figure 6. Each of the legs L-2 and L-3 is identical in construction with leg L-1, with the exception, of course, that they do not have a crown block supporting platform 76 mounted on the upper end thereof, or the platform P pivotally supported therefrom.

The upper legs 66b and 66c are each provided on the upper ends thereof with a bolt 100, with each of the bolts being adapted to cooperate with one of two slotted members 101 mounted on the outwardly disposed side pieces 77 to removably secure the upper ends of the legs L-2 and L-3 thereto after the leg portions 66b and 66c have been raised upwardly to the position shown in Figure 6. After the bolts 100 have been engaged with the members 101 and tightened up the derrick D is held together as an integral unit, and can be used for drilling operations in a conventional manner.

Although a number of hydraulic systems may be employed to actuate the cylinders used in erecting my derrick to the position shown in Figure 6, and causing it to collapse to the position shown in Figures 1 and 2, I have found it convenient to employ the hydraulic system shown in diagrammatic form shown in Figure 11.

A hydraulic pump 102 of the proper capacity is provided and mounted in a convenient location on the vehicle V, and is connected by a conduit 104 to a reservoir 105 that is filled with hydraulic fluid. Hydraulic fluid is discharged from the pump 102 when it is in operation into a conduit 106 which leads to a header 107. Each of the hydraulic cylinders 43, 43b, and 43c used in moving the lower leg portions 48, 48b, and 48c upwardly into a tripod position is connected by a conduit 108, 108b, and 108c respectively, to the header 107. Each of the conduits 108, 108b, and

108c has a valve 109, 109b, and 109c respectively provided therein, and situated between the header 107 and the hydraulic cylinder to which the conduit is connected. Extending from the lower portion of each of the cylinders 43, 43b, and 43c is a conduit 110, 110b, and 110c respectively, with each of the conduits having a valve 111, 111b, and 111c provided therein and located between the hydraulic cylinders from which the line extends to a return header 112 to which each of the conduits is connected.

Two discharge conduits 115 and 116 extend from the header 107 to opposite ends of the hydraulic cylinder 36, with the conduit 115 having a valve 117 mounted therein, and the conduit 115 being provided with a valve 118. Two conduits 119 and 120 extend from opposite ends of the cylinder 36 to the header 112, with conduit 119 having a valve 121 provided therein, and a valve 122 controlling the flow of fluid through the conduit 120.

The hydraulic cylinders 67, 67b, and 67c raise upper legs 66, 66b, 66c, and are connected to the header 107 by conduits 123, 123b, and 123c respectively. Each of the conduits 123, 123b, and 123c is provided with a valve 124, 124b, and 124c respectively, to control the flow of fluid to the cylinders 67, 67b, and 67c. The cylinders 67, 67b and 67c are connected to the return header 112, by conduits 125, 125b, and 125c respectively. Each of the conduits 125, 125b, and 125c is provided with a valve 126, 126b, and 126c respectively. One of the cylinders 75 is provided for each of the legs L-1, L-2, and L-3. Each of the cylinders 75 is provided with a conduit 130 that extends from the header 107 to both ends of the cylinder, with the flow of fluid through this conduit being controlled by a valve 131. A conduit 136 having a valve 137 positioned therein extends from the center of each cylinder 75 to the header 112. By the use of the above described piping the pistons situated in the cylinder 75 may be moved inwardly toward one another.

To move the pistons away from one another in the cylinder 75 a conduit 134 having a valve 135 positioned therein extends from the header 107 to the center portion of each cylinder 75. As hydraulic fluid is admitted to the cylinder 75 through the conduit 134, hydraulic fluid is displaced from the cylinder by movement of the pistons situated therein through the conduit 132, which conduit has a valve 133 situated between the cylinder and the header 112 to which the conduit is connected. As a safety measure to prevent rapid movement of the component parts of the derrick during the time it is being collapsed, by inadvertently opening the wrong valve or valves, the discharge of hydraulic fluid from the conduit 112 to the reservoir 12 is controlled by a valve 140 having a restricted orifice being placed in a conduit 141 leading thereto.

The operation of my invention is relatively simple. In Figures 1 and 2 it will be noted that when the derrick is in the collapsed position on the vehicle V the legs L-2 and L-3 are supported on their forward ends on a transversely positioned bracket 150 that is supported on uprights 151 having their lower ends affixed to the chassis portion 10. The legs L-1, L-2, and L-3 on their rearward ends have a cross piece removably affixed thereto, with the cross piece also being removably affixed to a convenient upwardly extending portion of the vehicle V to prevent jostling of the legs as the vehicle is moved over rough terrain. It will also be noted in Figure 1 that

the working platform P extends forwardly and has the engaging members 98 removably affixed to brackets 153 that extend downwardly from the rearward end of the vehicle. Thus, the working platform P not only serves as a support for a member of the crew when the derrick is in the erected position, but serves to hold the leg L-1 in a fixed position on the vehicle when the derrick is collapsed. It will be obvious that the engaging members 98 may be fabricated in a number of different forms so long as they are adapted to hold the working platform P in a substantially horizontal position when the derrick is in the erected form as shown in Figure 6, and to hold the platform in a fixed position when the derrick is in the collapsed state as shown in Figure 1.

In operating my device the vehicle V is moved to the desired location, and the pump 102 is placed in operation. The pump 102 can be actuated by either electrical means or an internal combustion engine. The valve 109 is then opened to permit hydraulic fluid to be delivered to the cylinder 43 which raises the leg L-1 to the position shown in Figure 4. Valves 109b and 109c are then opened which causes the legs L-2 and L-3 respectively, to be raised to the same position as that occupied by leg L-1. Valve 122 is then opened as well as valve 121, which permits hydraulic fluid to flow from the header 112 to the cylinder 36, with the result that the piston rod 35 is moved rearwardly to cause the two rearward chassis portions 11 to be moved from the position shown in phantom line in Figure 5 to the position shown in solid line in the same figure. It will be apparent that prior to the last operation being performed the alignment of the wheels 24 is changed from the position shown in Figure 3 to that shown in Figure 5 by rotating the crank or wheel 31 as previously explained.

With the legs L-1, L-2, and L-3 thus positioned, the platform P which previously has been held in an upwardly extending position by a cable 154 is permitted to pivot downwardly to a substantially horizontal position where the members 98 are engaged by the hooks 99. The cable 154 extends over one of the sheaves 80 or 81 to a winch 155 of conventional design that is conveniently located on the vehicle.

Hydraulic fluid is now admitted to the cylinder 67 by opening the valve 126, with the result that the piston rod 45 moves the leg portion 66 upwardly until it engages stops 160 which are affixed to the lower leg portion 48. Valve 135 is opened as well as valve 133 to permit piston rods 74 in the cylinder 75 to move outwardly and cause the stops 72 to pivot inwardly in order that the lower part of the upper leg portion 66 may rest thereon. Thus the weight of the crown block 76 and the working platform P is transmitted through the stops 72 to the lower leg portion 48, and this weight together with the weight of the leg portions 48 and 66 being transmitted by the jack 54 to the pressure plate 56.

Valves 124b and 124c are now opened to permit hydraulic fluid to be introduced into the cylinder 67b and 67c respectively, with the result that the upper leg portions 66b and 66c of the legs L-2 and L-3 are moved upwardly to a position where the engaging members 98 on the upper ends thereof can be removably affixed to the framework 76. My derrick D is now ready for operation, and draw works (not shown) are positioned between the spread chassis portions 11, and the drilling operation commenced after the

moving block is supported between the legs L-1, L-2, and L-3 from a cable (not shown) which extends over the crown block 79.

After the drilling operation is completed the engaging bolts 100 on the upper ends of the legs L-2 and L-3 are disconnected from the crown block supporting framework 76. The valves 111b and 111c are then opened, and due to the weight of the upper leg portions 66b and 66c on the piston rods 45b and 45c the leg portions move downwardly expelling fluid from the cylinders 43b and 43c to the header 112. Hydraulic fluid flows from the header 112 to the reservoir 105, but with its flow being restricted by the valve 140. Thus, due to the valve 140 having a restricted orifice, there can be no rapid movement of the component parts of my device as it is being placed in the collapsed position, even though one or more of the valves may be inadvertently opened. The working platform 87 is placed in the position shown in Figure 4 by simply reversing the operation previously described in moving the platform into a horizontal position. After the legs L-2 and L-3 have been placed in the collapsed position the valve 111 is opened which permits the upper leg portion 66 to move downwardly to the position shown in Figure 4. Prior to the leg portions 66, 66b, and 66c being moved downwardly, the valve 131 is opened as well as the valve 37 which causes the piston rods 74 to move inwardly and disengage the stops 72 from supporting the upper leg portions. The working platform P is placed in the position shown in Figure 4 by simply reversing the operation previously described in moving the platform into a horizontal position.

The lower leg portions 48, 48b, and 48c are now permitted to pivot downwardly into the position shown in Figures 1 and 2 by opening the valves 111, 111b, and 111c respectively. However, prior to the legs L-2 and L-3 being permitted to assume the horizontal position shown in Figures 1 and 2, the rearward chassis portions 11 are moved from the position shown in solid line in Figure 5 to that shown in phantom line in the same figure. This is accomplished by opening the valves 117 and 122, which permits fluid to be introduced into the cylinder 36 through the conduit 115, and fluid previously in the cylinder to be discharged through the conduit 120 to the header 112. After the rearward chassis portions 11 have been moved to the position shown in phantom line in Figure 5, the wheels 24 are aligned in position with the forwardly positioned wheels 23 by rotating the crank or wheel 31 as previously explained. The working platform P is now connected by the engaging members 98 to the bracket 153 situated on the rearward portion of the vehicle V. The forward portions of the legs L-2 and L-3 rest on the supporting bracket 150 on the chassis portion 10, while the rearward portion of the legs are removably connected to one another by the cross piece 152. The derrick now is in condition to be moved to a storage area or another location where a well is to be drilled by having a truck or tractor 160 shown in phantom line in Figure 1 engage the forward portion of the vehicle V in a conventional manner.

Although in the previous description of my derrick, I have mentioned the use of hydraulic cylinders 67b and 67c to move the upper leg portions 66b and 66c upwardly from their telescoped position, the same result can be achieved by use of the cable 154 that extends over one of

the sheaves 83 or 81 and is actuated by the winch 155. When my device is operated in this manner, the leg L-1 is extended upwardly its full length, and a hook 156 on the end of the cable 154 is caused to engage the two leg portions 66b and 66c to draw them upwardly sufficiently far to engage the crown block supporting frame 76 as previously explained. It will be apparent that the latter form of my invention can be constructed at less expense than the previously described form in that the two hydraulic cylinders 67b and 67c are eliminated.

While the above described forms of my invention are capable of achieving the objects and providing the advantages hereinbefore mentioned, it is to be understood that they are merely illustrative of the preferred forms of my invention, and that I do not mean to limit myself to the details of construction herein shown and described other than as defined in the appended claims.

I claim:

1. A portable derrick comprising a forward vehicle portion and a pair of rearward vehicle portions hinged to said forward portion for lateral movement with respect thereto; means effective to push said rearward portions apart and to draw them together; a derrick leg pivotally mounted at a point toward but spaced from its lower end on said forward vehicle portion; means effective to lower said leg so that its upper end extends rearwardly and its lower end forwardly of the forward vehicle portion; a derrick leg pivotally mounted at a point toward but spaced from its lower end on each of said rearward vehicle portions; means effective to lower the legs mounted on the rearward portions so that their upper ends extend forwardly and their lower ends extend rearwardly of said forward vehicle portion; means effective to raise said legs from a substantially horizontal position, after the rearward vehicle portions have been spread apart, into a tripod formation with their upper ends adjacent one another; and means effective to detachably secure together the upper ends of the legs to provide a rigid self braced structure.

2. A portable derrick comprising a forward vehicle portion and a pair of rearward vehicle portions hinged to said forward portion for lateral movement with respect thereto; means effective to push said rearward portions apart and to draw them together; a derrick leg pivotally mounted at a point toward but spaced from its lower end on said forward vehicle portion; means effective to lower said leg so that its upper end extends rearwardly and its lower end forwardly of the forward vehicle portion; a triangular frame pivotally mounted on the derrick leg mounted on the forward vehicle portion; detachable securing means on the derrick legs mounted on the rearward vehicle portions whereby said triangular frame is secured to the latter derrick legs when in erected position to provide a stand for pipe and the frame may be disconnected from the latter legs to enable them to be brought to a horizontal position; a platform supported on said frame for the use of personnel; means effective to lower the legs mounted on the rearward portions so that their upper ends extend forwardly and their lower ends extend rearwardly of said forward vehicle portion; means effective to raise said legs from a substantially horizontal position, after the rearward vehicle portions have been spread apart, into a tripod formation with their upper ends adjacent one another; and means

11

effective to detachably secure together the upper ends of the legs to provide a rigid self-braced structure.

3. A portable derrick as set forth in claim 2 and in addition comprising securing means mounted on the rearward vehicle portions adapted to engage the triangular frame when the tripod legs are in horizontal position to secure the tripod leg mounted on the forward vehicle portion to the rearward vehicle portions.

4. A portable derrick having a plurality of wheel supported portions movably connected together, comprising: a derrick leg mounted on each of said wheeled portions; a double acting hydraulic cylinder and piston mounted on one of said wheel supported portions; connecting means between said piston and the other wheel supported portions and effective to push the wheeled portions apart to position the derrick legs for erection, and bring them together to provide a vehicle for transportation of the derrick; a hydraulic cylinder and piston mounted on each of said wheel supported portions for raising and lowering the derrick leg mounted on each wheeled portion; a hydraulic system in which all said hydraulic elements are connected; a pump connected to said hydraulic system for supplying fluid under pressure to said system; a reservoir connected between the pump and a pipe returning fluid from said system to the reservoir; a valve in said pipe returning fluid to the reservoir, said valve being effective to restrict the flow of fluid through said pipe to prevent excessive speed in lowering the derrick legs; individual valves controlling the flow of fluid to and from each of said hydraulic elements; and means for detachably securing together the upper ends of said legs when in erected position to form a self-braced derrick.

5. A portable derrick having a plurality of wheel supported portions movably connected together, comprising: a derrick leg formed of telescopic sections mounted on each of said wheeled portions, the outer sections being pivotally mounted on said wheeled portions; a double acting hydraulic cylinder and piston mounted on one of said wheeled portions; connecting means between said piston and the other wheel supported portions and effective to push the wheeled portions apart to position the derrick legs for erection and bring them together to provide a vehicle for transportation of the derrick; a hydraulic cylinder and piston mounted on each of said wheel-supported portions and connected to the outer sections of the derrick legs mounted thereon for raising the derrick legs; a hydraulic cylinder and piston mounted within each derrick leg and connected to the inner sections thereof and effective to project the inner sections of the derrick legs outwardly; detent means mounted on the derrick legs and effective to hold them in extended position; hydraulic means effective to release said detent means to enable said derrick leg sections to be telescoped; a hydraulic system in which all said hydraulic elements are connected; a pump connected to said hydraulic system for supplying fluid under pressure to said system; a reservoir connected between the pump and a pipe returning fluid from said system to the reservoir; a valve in said pipe returning fluid to the reservoir, said valve being effective to restrict the flow of fluid through said pipe to prevent excessive speed in lowering the derrick legs; individual valves controlling the flow of fluid to and from each of said hydraulic elements; and means for

12

detachably securing together the upper ends of said legs when in erected position to form a self-braced derrick.

6. A portable derrick that may be erected to provide a self-braced tripod structure which includes: a forward chassis portion and two rearward chassis portions pivotally connected thereto; three legs, with one of said legs pivotally mounted on said forward chassis portion, and each of the other two legs pivotally supported on one of said rearward chassis portions, with said legs occupying a longitudinally extending position on said chassis portions when said derrick is in a portable condition; a plurality of wheels supporting said forward and rearward chassis portions; means to align said wheels supporting said rearward chassis portions in a direction to permit said rearward chassis portions to be pivoted toward or away from one another; a hydraulic cylinder mounted on said forward chassis portion; a piston rod mounted in said cylinder; linkage means connecting said rod to said rearward chassis portions; a source of hydraulic fluid under pressure that actuates said piston rod to spread said rearward chassis portions into a derrick erecting position and to retract said rearward chassis portions into a derrick transporting position; three hydraulic cylinders, with one of said cylinders pivotally mounted on each of said chassis portions; three piston rods, with each of said rods mounted in one of said three hydraulic cylinders and pivotally connected to one of said legs; means connecting said three cylinders to said source of hydraulic fluid, and each of said cylinders when actuated, pivoting one of said legs upwardly into an inclined vertical position; three extension legs, with each of said extension legs telescopically mounted on one of said legs; three hydraulic cylinders, with one of said cylinders mounted on each of said legs; three piston rods, with one of said rods mounted in each of said leg supported cylinders and each of said rods connected to said extension legs associated therewith; means connecting said leg supported cylinders to said source of hydraulic fluid whereby said extension legs may be extended or retracted; a crown block assembly mounted on the upper end of one of said extension legs; means to removably join the upper ends of said extension legs to said crown block assembly when said legs and extension legs are in a derrick forming position; a triangularly shaped platform pivotally supported from one of said legs; means to lock said platform to the other of said legs in a substantially horizontal position when said legs are in a derrick forming position; and means to lock said platform to said rearward chassis portions to hold said legs in position thereon when said derrick is in a portable condition.

7. A portable derrick that may be erected to provide a self-braced tripod structure which includes: a forward chassis portion and two rearward chassis portions pivotally connected thereto; wheels supporting said chassis portions; three legs, with one of said legs pivotally supported on each of said chassis portions, with said legs occupying longitudinally extending positions on said chassis portions when the derrick is in a portable condition; three extension legs with one of said legs telescopically mounted on each of said legs; hydraulic means to pivot said rearward chassis portions away from and toward one another; hydraulic means to pivot each of said legs upwardly to an inclined vertical position; hydraulic means to extend and retract said extension legs; a source

of hydraulic fluid to actuate said hydraulic means; control means to regulate the flow of fluid from said source to said hydraulic means; a crown block assembly mounted on the upper end of one of said extension legs; means to removably join the upper ends of the other two of said extension legs to said crown block when said legs and extension legs are in a derrick forming position; a triangularly shaped platform pivotally mounted on one of said legs; means to lock said platform in a horizontal position to the other two of said legs when said legs are in a derrick forming position; and means to lock said platform to said rearward chassis portions to hold said legs in position thereon when said derrick is in a portable condition.
